ATTORNEY

UNITED STATES PATENT OFFICE.

CHARLES NEHRKE, OF BROOKLYN, NEW YORK, ASSIGNOR TO FRITZ P. MANSBENDEL,
OF BROOKLYN, NEW YORK.

MASSAGE APPARATUS.

1,308,805.

Specification of Letters Patent.

Patented July 8, 1919.

Application filed November 3, 1916, Serial No. 129,274. Renewed December 4, 1918. Serial No. 265,317.

To all whom it may concern:

Be it known that I, CHARLES NEHRKE, a citizen of the United States, and a resident of Brooklyn, in the county of Kings and 5 State of New York, have invented certain new and useful Massage Apparatus, of which the following is a specification.

The invention relates to vacuum massage apparatus, more particularly to a small, 10 compact and portable device which may be conveniently operated, for example manually. It has for its object to provide an inexpensive apparatus of this character in which the massage action, secured by moving a vacuum cup over the surface to be treated, may be combined with the beneficial effects produced upon the skin by the action of light.

In the accompanying drawings, which 20 illustrate the invention—

Figure 1 is an elevation of the improved massage apparatus; and Fig. 2 is a vertical section therethrough.

Fig. 3 is a horizontal section, taken on 25 the line 3—3, Fig. 2.

Similar characters of reference designate corresponding parts throughout the several views.

Referring to the drawings, 10 designates 30 a container or cylinder suitably closed at the forward end as by means of a block of insulation material 11, the outer portion thereof having a lip 12 and forming a cup 13. In this block 11 is mounted a socket 35 adapted to receive an electric lamp 14 which is designed to be lighted from a suitable source of electricity such as a battery 15 connected thereto through a flexible cord 16 or the like. The other end of the cylinder is 40 closed by means of a cap 17 providing a bearing through which is adapted to move a piston rod 18 or the like, having an outer head or actuating knob 19 and a piston 20 for reciprocation within the cylinder 10. 45 The piston may consist of a washer 21 of leather or the like and be held between two plates 22 which are secured to the inner end of the piston rod by means of nuts 23. A coiled spring 24 is mounted in the cylinder 50 10 between the block 11 and the said piston 20, whereby the latter is normally forced

outwardly into the position indicated in full lines in Fig. 2 of the drawings.

To operate the apparatus, the piston is forced inwardly to the position shown in 55 dotted lines, Fig. 2, by exerting suitable pressure on knob 19, in opposition to the spring 24. At the same time, the vacuum cup 13 is pressed against the skin, the lamp 14 having been previously lighted. The 60 inward motion of said piston forces the air contained in cylinder 10 out through a port 25 of the block 11; and upon releasing the pressure on the said piston, the latter is automatically returned under the action of 65 spring 24, creating a vacuum in the cup 13 and thereby affecting the skin over which said cup is moved, and, moreover, subjecting the same simultaneously therewith to the action of intense light produced by the 70 lamp 14. Under the vacuum, the skin, in addition to the cleansing and stimulating effect thus produced thereon, is placed in a condition to be particularly responsive to the action of the light from the lamp 19 75 whose intensity may be increased by means of a parabolic reflector 26 mounted about the same in the interior of the cup 13.

I claim:

1. In an apparatus of the character set 80 forth, a cylinder, and a piston operating therein to produce a vacuum; a plug closing one end of said cylinder and terminating in a vacuum cup communicating with the interior of said cylinder; an electric lamp mounted in said plug; and resilient means included between said plug and said piston.

2. In apparatus of the character set forth, 85 a cylinder, and a piston operating therein to produce a vacuum; a plug closing one 90 end of said cylinder and terminating in a vacuum cup communicating with the interior of said cylinder; an electric lamp mounted in said plug, and a reflector for same mounted in the vacuum cup; and resilient means included between said plug 95 and said piston.

Signed at New York, in the county of New York and State of New York, this 30th day of October, A. D. 1916.

CHARLES NEHRKE.
